PHOTO-ELECTRIC TUBE

Earl D. Wilson, Wilkinsburg, Pa., assignor to
Westinghouse Electric & Manufacturing Com-
pany, a Corporation of Pennsylvania

Application February 20, 1929. Serial No. 341,344

8 Claims. (Cl. 250—27.5)

This invention relates to photo-electric tubes and particularly to photo-electric tubes in which a shield is provided between the anode and the cathode.

5 As indicated in the copending application of Allen A. Shoup, Serial No. 340,314 filed Feb. 15, 1929, it is desirable, when a high-frequency carrier current is to be used with a photo-electric tube, to provide a shield in order that the electro-10 static capacity between the anode and the cathode will not convey a current to the amplifier with which the photo-electric tube is used.

It is an object of this invention to provide such an arrangement of the elements of the photo-electric tube that the shielding means will not interfere with the illumination of the photo-sensitive surface.

15 It is a further object of this invention to arrange the elements of the photo-electric tube and their supports in such a way that the cell is convenient to manufacture and the shielding will be effective.

It is a further object of this invention to provide complete and effective shielding between the cathode and both the anode and the conductor leading thereto.

20 Other objects of the invention and details of the construction will be apparent from the following description and the accompanying drawing in which:

Figure 1 is an axial section, and

Fig. 2 is a transverse section.

The photo-electric tube comprises a glass envelope 1 provided at each end with a press 2 and 3, respectively. At the end having the press 2, which, as illustrated, is the upper end, the photo-electric tube is supplied with any suitable base 4 equipped with pins 5 to cooperate with a standard socket. A conductor 6 extends through the press 2 and establishes connection between one of the pins 5 and the cathode 7.

25 The cathode is in the form of a sheet of material, preferably flat except that a margin 8 thereof is at an angle to the main body of the cathode. The sheet is supported upon the standard 6 and a supplementary standard 9 mounted in the press 2. If an unusually large photo-tube is built, additional standards may be provided for the purpose of supporting the cathode and preventing excessive vibration.

An anode 11 is mounted in the press 3. Preferably this has the form of a straight wire or rod of small diameter. The rod extends through the press 3 and is conductively connected with a wire 12 extending to the outside of the tube. The

top of the press 3 is furnished with a cylindrical glass boss 13 surrounding the foot of the anode.

A helix 15 of fine wire of relatively large pitch is mounted to surround the anode 11. Any convenient means for holding the helix in place may be employed, but I prefer a rod 16, soldered, welded or otherwise rendered metallically integral with each whorl of the helix. A conductor 17 extends through the press 3 and is connected metallically with the standard 16 as shown 65 at 18. This connection is preferable by welding, but any metallically continuous and mechanically strong connection will suffice.

A disk 21 is supported upon the end of the conductor 17. The portion of the conductor 17 70 between the press and the disk is oblique in order to better support the disk, and the lower end of the standard 16 is at an angle to the remainder thereof in order to make a convenient joint with the bent end of the conductor 17.

A metallic cap 22, secured to the disk 21, encloses a volatilizable pellet. Supported at the top of the standard 16, is a disk 23 of approximately the same diameter as the helix 15.

A metallic sleeve 25, preferably nickel, of the 80 same diameter as the helix 15, surrounds the boss 13 and is located in alignment with the helix. The disk 21 has a central opening of sufficient size to accommodate the sleeve 25 and the standard 16. 85

A metallic sleeve 24 outside the photo-tube extends from the end of the photo-tube slightly past the disk 21, and serves as an external electrostatic shield.

In the operation of the device, the photo-tube 90 is so placed that the light enters through the transparent wall of the envelope at such an angle to the plane of the main portion of the cathode that the shadow of the anode 11 and helix 15 does not fall upon this part of the cathode. The 95 light thus received upon the main part of the cathode is reflected and most of the reflected light may be intercepted by the marginal portion 8 of the cathode. In this way, substantially the same extent of cathode surface is subjected to 100 the light as if the anode 11 and the helix 15 were not present to obstruct the light and the light were received normal to the main cathode surface.

The light is ordinarily supplied to the cathode 105 by focusing upon the cathode an image of an illuminated slit. With the light received at an acute angle as just described, the image of the slit is wider because the cathode surface is oblique to the light beam. With the best adjustment, 110

the image of the slit is made approximately to coincide with the main portion of the cathode. The larger portion of the light thus received upon the cathode is reflected by specular reflection and consequently arrives at the marginal surface 8.

The cathode surface consists of a thin plating of silver upon a copper base. Upon the silver, photo-electric material such as potassium, caesium, or a combination of the two is deposited. The preparation of this deposit is made in a way familiar to those skilled in the art and need not be described herein.

In use, the phototube may be connected into a circuit by means of which an alternating difference of potential is established between the anode 11 and the cathode 7. It is undesirable that the capacity effect between these two elements should convey current through the phototube, and the helix 15 with its associated parts constitutes a shield for preventing such capacity effect.

The helix 15 surrounds the anode and extends beyond the upper end thereof. At this end the envelopment of the anode is completed by the disk or cap 23 which closes the shield at this point.

At the lower end of the anode, the completion of the shielding is effected by the metal sleeve 25. Any lines of force extending from the cathode must arrive at the lower end of the sleeve 25 to produce any result at the anode 11, but the arrival of such lines of force is prevented by disk 21, which completely fills the cross section of the phototube except for a very small clearance at the inside of the glass wall and a small clearance about the sleeve 13.

Any lines of force from the cathode which extend to the outside of the phototube are prevented from reentering and arriving either at the anode 11 or at the conductor 12, associated therewith by the metallic sleeve 24 which surrounds the disk 21 and extends so far beyond the end of the photo tube that negligibly few lines of force from the cathode reach the lower end of the sleeve.

In the preparation of the photo tube an alternating electro-magnetic field parallel to the axis of the anode is applied, with the result that eddy currents are set up in the disk 21 and the disk is heated. The cap 22, containing the volatizable pellet is heated to such a temperature that the pellet disintegrates and photo-electric material therefrom is released to be deposited upon the cathode.

Many variations of the structure described herein will occur to those skilled in the art. The explicit description of only a single form is not to be construed as a limitation. No limitations are maintained except those required by the prior art or expressly stated in the claims.

I claim as my invention:

1. A photo-electric tube consisting of a cathode comprising a main substantially flat portion and other electrodes located in front of and at a distance from said portion, whereby, when light

is received at a sufficiently oblique angle to said flat portion, the shadow of said other electrodes will not fall thereon, said cathode also comprising a portion at such an angle to said first-named portion that most of the light received at said oblique angle and reflected by said first-named portion will be intercepted by said second-named portion.

2. A photo-electric tube comprising an evacuated envelope having two presses, one at each end thereof, a cathode of sheet material supported from one of said presses, a support therefor including a conductor extending through the press to the exterior of the envelope and an anode and a shield separately supported from the other press by means of supporting members, said supporting members each including a conductor extending through said last-named press to the exterior of the envelope.

3. A photo-electric tube comprising an evacuated envelope having two presses, one at each end thereof, a cathode of sheet material supported from one of said presses, a support therefor including a conductor extending through the press to the exterior of the envelope, an anode and a shield separately supported from the other press by means of supporting members, said supporting members each including a conductor extending through said last-named press to the exterior of the envelope and a metal sleeve on the exterior of the envelope cooperating with said shield to complete the electrostatic separation of the anode from the cathode.

4. A photo-electric tube comprising a cathode, an anode, a helix surrounding said anode, a disc closing one end of said helix and means at the other end thereof for completing the shielding of the anode.

5. A photo-electric tube comprising a cathode, a press, an anode mounted in said press, a helix surrounding said anode, a metallic sleeve mounted on said press in alignment with said helix and extending from the helix beyond the point of entrance of the anode into the press, a disk surrounding said sleeve and a sleeve outside the photocell extending from the plane of said disk to beyond said press.

6. A photo-electric tube comprising a press, an anode mounted in said press, a helix surrounding said anode, a metallic sleeve mounted on said press in alignment with said helix and extending from the helix beyond the point of entrance of the anode into the press, a disk surrounding said sleeve and a sleeve outside the photocell extending from the plane of said disk to beyond said press.

7. A photo-electric tube comprising a cathode, an anode, a helix surrounding the anode, a disk concentric with said helix and conductively connected thereto.

8. A cylindrical photo-tube comprising an envelope, an anode mounted at one end thereof, a cathode mounted at the opposite end and a metallic sleeve surrounding the tube at the anode end and extending beyond the point of entrance of the anode into said envelope.

EARL D. WILSON. 140
